WILFORD R. SPROUL, OF CHICAGO, AND HUGO LAYER, OF WINNETKA, ILLINOIS, ASSIGNEES TO E. W. SPROUL COMPANY, OF CHICAGO, ILLINOIS, A CORPORATION OF ILLINOIS.

FORM FOR CONCRETE WALL CONSTRUCTION.

Application filed December 16, 1926. Serial No. 155,128.

This invention relates to slip forms for the construction of hollow concrete walls.

The general object of the invention is the provision of a construction for forms of this type, which may be manipulated easily and rapidly in the building up of the wall, and which eliminates the necessity for special supporting arrangements for reinforcing members which are to be embodied in the wall structure.

A particular object is the provision of a construction which facilitates the placing of tie rods employed for the tying together of the parallel sections of the hollow wall.

Another object is the provision of an improved cradle or shield device for closing the joint between adjacent sections of the form sheathing, which shield device will facilitate the placing of the tie rods and may be manipulated in common with the other portions of the form in the elevating operation.

Other and further objects of the invention will be pointed out or indicated hereinafter, or will be apparent to one skilled in the art upon an understanding of the invention or its employment in practice.

In the drawing forming a part of this specification we illustrate one structural form in which the invention may be embodied, but it is to be understood that this is presented by way of example only, and that the invention as defined in the appended claims is not to be regarded as limited to this particular embodiment or the details thereof.

In said drawing Fig. 1 is a sectional elevation of a slip form embodying our invention showing the manner in which it is utilized in the construction of a hollow concrete wall.

Fig. 2 is a detail in the nature of a horizontal section through the end portions of adjacent inner form sections, this section being taken on approximately line 2-2 of Fig. 3.

Fig. 3 is an end elevation of one of the inner form sections and the joint shield or cradle associated therewith.

Fig. 4 is a perspective view of a joint shield or cradle.

This invention relates to that type of concrete wall forms which are customarily des-

ignated slip forms, and which are characterized by the fact that they are arranged so as to be elevated at intervals during the building up of the wall to form a mould for the reception of pourings of concrete on top of portions of the wall formed by previous pourings within the form while it was in a lower position. The nature of the present improvements will be most quickly ascertained by reference immediately to the illustrative construction shown. In the illustration, the reference character 10 designates the outer plates or form sheathing which form the mould walls for the outer sides of the wall under construction. These outer mould plates extend for a desired distance in the longitudinal direction of the wall under construction and are carried in a suitable elevating frame 11. In this frame are threaded the jack-screws 12 which have rotatable bearing on clamps 14 which are connected to the rods 15. The reference character *w* designates the wall under construction, which, it will be observed, is of the hollow type having a cavity or space between the opposite parallel wall portions. It will be understood that there is a series of the frames 11 disposed at intervals longitudinally of the form and connected by the stringers 10^a which carry the form plates 10. At intervals along the course of the wall are disposed the vertical bars 15 which are to be embodied in the wall as reinforcing elements. These bars 15 are also utilized as purchase members in the operation of elevating the form. The clamps 14 are clamped into fixed engagement with the rods, and the screws are then turned, with the result that the frame is gradually elevated on their threads. The mould for the inner surfaces of the hollow wall is provided by the inner mould plates 16. These inner mould plates are constructed in sections, with the sections in alignment and slightly spaced apart at their ends, as illustrated in Fig. 2. These sections are carried

on the frame 11, being affixed thereto by means of the rods 17. Consequently, the elevation of the frame raises the inner mould plate coincidentally with the elevation of the outer mould plates 10. As is well understood by one familiar with the operation of slip forms, the space interven-

ing between the outer wall plates and the facing inner wall plates forms the mould cavity into which the concrete is poured for the building up of the wall. After a certain depth of concrete has been poured in these mould cavities, it is allowed to set to a proper hardness and stability, and then the form is elevated in the manner above described so as to extend the mould cavity 10 upwardly for the reception of a new pouring.

One of the reasons for the construction of the inner mould in sections is to accommodate transverse tie rods 18, which it is desirable frequently to place in the structure at intervals for the purpose of tying the opposite portions of the wall together across the intervening space. For the purpose of closing the space between the ends of adjacent 20 mould sections, to prevent the fluid concrete from running out through that gap, we provide a shiftable shield member 19. This may be constructed conveniently of metal, with a web portion 19^a of a width corresponding with that of the inner form section 16 and parallel flanges 19^b at the opposite margins of the web, said flanges being of sufficient width to overlap the outer surfaces of the adjacent form sections across 30 the space intervening between said sections. The flanges 19^b extend for some distance below the lower margin of the web 19^a, and are provided with downwardly opening slots 19^c at their lower ends. At their upper 35 ends they are provided with inwardly deflected portions or shoulders 19^d of sufficient length to extend across the top portions of the inner form plates. Adjacent the upper portion, the web 19^a is provided 40 with the apertures 19^e to afford hand hold portions whereby the shield or cradle device may be grasped.

For an understanding of the operation of the apparatus, let it be assumed that a 45 portion of the wall has been poured and set, the form sections 16 and the shield member 19 being in position to form the inner mould surfaces for the opposite wall portions. It being now desirable to elevate the form to receive a new pouring of concrete as a 50 further increment of the wall construction, the screws are turned down, thereby elevating the outer form plates as well as the inner form sections 16. As the latter are 55 elevated, they engage the flanges or shoulders 19^d of the shield member and carry the shield member upwardly with them. When the form has been elevated to the desired extent, if it is desirable at this point 60 to insert some of the tie rods, the shield member is further drawn upwardly, by hand, to a sufficient extent to permit the insertion of the tie rod between the ends of form sections 16, under the flanges 19^b, and 65 permit the proper positioning of the tie rod

with its ends resting on top of the concrete in the opposite wall sections. The shield member is now replaced and pushed downwardly so that the slots 19^c embrace the tie rod and the lower ends of the flanges 19^b 70 extend down for a limited distance between the mould surfaces of the form sections and the inner surfaces of the concrete wall portions. Thus the tie rod is held accurately in position for the next pouring of concrete, 75 and the space between the adjacent form sections is effectively closed on both sides by the shield member, to prevent the fluid concrete from running out of the mould cavity. The next pouring of concrete is 80 then made, and allowed to set, whereupon the elevating operation may be repeated, as above described. It will be understood, of course, that the relative height of the shield member and the form sections need not be 85 in the particular proportion shown in the drawing.

One of the pronounced advantages of this apparatus lies in the fact that it eliminates the necessity for any temporary or individual supporting arrangement for maintaining the tie rods in position independently of the form. Consequently they may be inserted as desired during the building up of the wall, and they are held definitely in 95 position so that they will not be displaced by the pouring or raking of the concrete as it is distributed.

What we claim is:

1. In a slip form for concrete wall construction, the combination of form sections arranged end to end in spaced relation, means for elevating the sections, and a shield member overlapping the mold surfaces of adjacent sections to close the space between them, said shield member being engageable with said sections for elevating movement therewith. 100

2. In slip forms for concrete wall construction, in combination, form sections arranged end to end in spaced relation and having mold surfaces at opposite sides, a shield member having portions overlapping said mold surfaces to close the space between the sections, and means for elevating the mold sections. 110

3. In slip forms for concrete wall construction, in combination, form sections arranged end to end in spaced relation and having opposite mold surfaces for shaping the inner surfaces of opposite concrete wall portions, means for elevating the form sections, and a shield member having portions overlapping said mold surfaces of the adjacent form sections to close the space between them, said portions having slots at their lower ends aligning with the space between the form sections for reception of a tie rod extending between the wall portions. 120

4. In a slip form for concrete wall con- 125

struction, a shield member comprising a web portion with lateral flange portions extending at right angles from opposite margins thereof, said flange portions extending below the lower margin of the web portion and provided with downwardly opening slots and means at the upper portion of said shield

member whereby it may be engaged for lifting movement.

In testimony whereof we have hereunto ¹⁰ subscribed our names.
